UNITED STATES PATENT OFFICE

2,037,129

ELECTRIC GAS GUN

George F. Hilts, Grand Rapids, Mich.

Application August 8, 1934, Serial No. 739,013

1 Claim. (Cl. 89—28)

This invention appertains to new and useful improvements in means for catapulting gas bombs or containers and the principal object of the invention is to provide a catapult which is 5 electrically operated and capable of being remotely controlled to effect a discharge of a gas bomb in an effective manner.

Another important object of the present invention is to provide a gas bomb catapult especially adapted for use in banking houses and similar places where valuables are kept and which, in construction, is not readily observed so that its operation will be a surprise and an overcom- 10 ing factor in the treatment of malfeasors.

15 Other important objects and advantages of the invention will become apparent to the reader of the following specification.

In the drawings:

Figure 1 is a vertical sectional view through the 20 novel catapult.

Figure 2 is a horizontal sectional view through the casing of the catapult.

Figure 3 is an end elevational view looking toward the muzzle of the catapult with the dome 25 removed.

Figure 4 is a fragmentary detailed longitudinal sectional view through a tool for removing and placing the gas bombs or cartridges.

Figure 5 is a fragmentary elevational view of 30 the tool.

Referring to the drawings wherein like numerals designate like parts, it can be seen that numeral 5 represents a base having a standard 6 thereon. Pivotally connected to this standard 6 is the body 7 having a bore 8 therein for containing the spring 9. The body 7 has a counter-bore 10 for receiving the end portion *a* of the barrel 11, which barrel is provided with a stud 12 engageable into the bayonet slot 13 of the body 7.

40 The barrel 11 is provided with notches 14 at its discharge end and, as can be seen in Figure 1, a shoulder 15 is provided on the barrel and has a beveled side portion which can wedge against the body 7 with the stud 12 engaged in the slot 13.

45 Numeral 16 represents a raised portion on the body 7 supporting the bracket 17 upon which is mounted the electro-magnet 18. This electro-magnet is adapted to actuate the armature 19 situated below the same, the armature being pivotally connected to the coupling member 20, which, in turn, is provided with a threaded socket for receiving the threaded upper end of the pin 21. This pin extends through a bore 22 in the raised portion 16 and a spring 23 in this bore

serves to normally urge the pin downwardly to engage the head 24 which has a circumferentially extending groove 25 therein for receiving the said pin 21. The spring 9 impinges the head 24 and when the pin 21 is engaging in the groove 25 thereof, is under tension.

Numerals 26—26 represent slotted and arcuate shaped arms which extend downwardly from the body 7 and through which the bolts 27 extend. Nuts 28 thereon can be tightened against these 10 arms to maintain the body 7 in the proper adjusted position.

Wires 29 from the electro-magnet 18 extend to the socket 30 and all that is required is to plug in a current supply circuit with this plug socket 15 30 to accomplish the result desired.

Figures 4 and 5 represent a tool for inserting and removing the gas containers.

The tool consists of an elongated tube 29 provided with a fixed collar 30 thereon and a spring 20 interposed between the collar 30 and a supplemental collar 31. Numerals 32—32 represent slots in the tube and these slots at one end each have an offset 33 disposed in one direction and at its opposite end an offset 34 disposed in the op- 25 posite direction.

A cross rod 35 at one end of the tube 29 serves as a handle for the tool.

It will be observed that, in removing a cartridge after the catapult has been fired, the tube 29 is 30 inserted into the barrel 11 with the teeth 35a on the supplemental collar 31 engaging into the notches 14 of the barrel 11. Pressure is exerted until the tube 29 can be rotated so that the cross pin 36 through the collar 31 can engage into the 35 offset 33 of the slots 32—32. Now by rotating the barrel 11, the same can be disconnected from the bayonet slot 13.

In placing another bomb, the gas cartridge is 40 inserted into the barrel 11. The collar 31 is now permitted to go down to the offset 34 where the collar pin 36 is permitted to enter the offset 34. The tube 29 is now inserted into the barrel 11 and the barrel inserted into the body 7. Thus the tool can be forced against the barrel 11 to engage 45 the stud 12 with the bayonet slot 13 without likelihood of damaging the gas cartridge or container.

Numeral 37 represents a dome of frosted glass or some similar material which is apt not to attract the attention of wrongdoers so that they will have 50 an opportunity to damage the same before it can be placed into operation.

While the foregoing specification sets forth the invention in specific terms, it is to be understood that numerous changes in the shape, size, 55

and materials may be resorted to without departing from the spirit and scope of the invention as claimed hereinafter.

Having described the invention, what is claimed as new is:

A device of the class described comprising a pivotally mounted body having a bore therein, and a reduced cavity in the rear thereof communicating with said bore, a cartridge discharging hammer in said bore, a coil spring in said cavity, one end of said spring being secured to the body and the other end thereof to said hammer, said hammer being provided with an annular groove therein, a vertically and slidably mounted pin in the top portion of said body adjacent said cavity, one end of said pin projecting into the bore in its innermost position, and adapted to ride in the annular groove of said hammer to

maintain the same in cocked position, a coil spring normally maintaining the pin in said innermost propped position, an armature secured to the outer free end of said pin, magnetic means for actuating said armature to move the pin out of engagement with said hammer, said body adjacent its outer edge being provided with an arcuate shaped bayonet slot, the inner side portion adjacent the outer end gradually tapering downwardly and inwardly forming a cam surface, and a barrel having a projecting pin thereon receivable in said bayonet slot and a tapered shoulder cooperating with the cam surface of the body secured in said body, the free end of said barrel having spaced longitudinally extending notches therein. 10 15

GEORGE F. HILTS.
